(57) **CLAIM**

The ornamental design for a bottle, as shown and described.

DESCRIPTION

FIG. 1 is a perspective view from the above and one side of the bottle showing a new design;

FIG. 2 is a side view thereof;

FIG. 3 is a side view from the other side thereof;

FIG. 4 is a plan view thereof; and,

FIG. 5 is an underneath plan view thereof.

The broken lines shown in the drawings are for illustrative purposes only and form no part of the claimed design.
